[57] **CLAIM**

The ornamental design for a multi-position body support, as shown and described.

DESCRIPTION

FIG. 1 is a perspective view of a multi-position body support, which embodies our design;

FIG. 2 is a front elevational view thereof;

FIG. 3 is a rear elevational view thereof;

FIG. 4 is a right side elevational view thereof and which the left side elevational view is a mirror image;

FIG. 5 is a plan view thereof;

FIG. 6 is a bottom view thereof;

FIG. 7 is a perspective view of a second embodiment of a multi-position body support, which embodies our design;

FIG. 8 is a front elevational view thereof;

FIG. 9 is a rear elevational view thereof;

FIG. 10 is a right side elevational view thereof and which the left side elevational view is a mirror image;

FIG. 11 is a plan view thereof; and,

FIG. 12 is a bottom view thereof.
